UNITED STATES PATENT OFFICE

GUSTAV EGLOFF AND JACQUE C. MORRELL, OF CHICAGO, ILLINOIS, ASSIGNORS TO UNIVERSAL OIL PRODUCTS COMPANY, OF CHICAGO, ILLINOIS, A CORPORATION OF SOUTH DAKOTA

PROCESS OF CRACKING HYDROCARBONS

Application filed June 28, 1926. Serial No. 118,903.

This invention relates to improvements in process of cracking hydrocarbons, and refers more particularly to that type of process in which the oil is passed through heating coils, thence to an expansion chamber, thence to a dephlegmator where the heavier insufficiently cracked portions are condensed, and preferably retreated.

In processes of this character, the residue from the expansion chamber, contains more or less carbonaceous or pitchy material which if it is rerun through the cracking coils, has a pronounced tendency to clog or choke them up.

The object of the present invention is to break down the heavy more or less solid or pitchy coke-like materials into more or less colloidal form where they are held in suspension in the liquid portions of the residue.

This liquid residue with the colloidal suspension is then passed again either through the same or another cracking coil, and again subjected to cracking conditions of heat and pressure. Such process obviously increases the yield of gasoline inasmuch as more of this colloidal material or heavy residue is converted into gasoline than is now the case.

The invention will be understood from the following description, reference being had to the accompanying drawing, in which the single figure is a more or less diagrammatic view of the apparatus for carrying out this invention.

Referring to the drawings, 1 designates a furnace in which is mounted the heating coil 2 connected by transfer line 3 having valve 4, to the expansion chamber 5. In the furnace may, if desired, be a second heating coil 6 connected by transfer line 7 having valve 8 to the expansion chamber 5. The vapors pass out of the expansion chamber through the vapor pipe 9 having valve 10 to the lower side of the dephlegmator 11. The vapors pass out of the top of the dephlegmator 11 through the pipe 12 controlled by the valve 13 to the condenser coil 14 and the receiver 15. This receiver 15 is provided with gas outlet pipe 16 controlled by valve 17 and with liquid drawoff pipe 18 controlled by the valve 19. The reflux condensate from the system may

be drawn off through the pipe 20 and hot oil pump 21 back to the main feed pipe 23, which feed pipe may be supplied with raw oil through the feed line 24 and raw oil pump 25.

The residue may be drawn off the bottom 55 of the expansion chamber through the residue drawoff pipe 26 controlled by valve 27, and thence passed continuously through a colloid mill 28, and thence through the line 29, pump 30 and line 31 to the second heating coil 6. 60 If the liquid residue is too hot to enter the colloid mill, it may be passed to the cooler 28' shown.

If desired, the second heating coil 6 might perhaps be dispensed with, and the residue 65 passed through the branch 32 to the line 23, the branch 32 having the valve 33.

The process may be carried out as follows:

The oil is passed through the first heating coil 2 and thence delivered at a transfer temperature of say 900° F. to the expansion chamber 5. The vapors pass to the dephlegmator 11 where the insufficiently cracked portions are condensed as reflux condensate and redelivered to the coil 2 for further cracking. 75 The uncondensed vapors pass out of the top of the dephlegmator into the water condenser and receiver.

As a feature of the invention, the liquid residue containing the pitch, coke or carbonaceous material heretofore referred to, is passed continuously through a colloid mill where the solid or pitch-like particles are broken up into colloidal form, and remain in colloidal suspension in the liquid portion of 85 the residue. This residue so treated, is then passed back to the system in the manner heretofore described. The whole system may be maintained under a uniform pressure of 200 pounds more or less, and the temperature may 90 be 850° F. more or less.

By means of the process just described, we materially increase the yield of gasoline from a given charge of oil, and as part of a continuous operation.

We claim as our invention:

1. A process of cracking hydrocarbon oil, consisting in subjecting the oil to cracking conditions of temperature and pressure, removing and collecting the cracked vapors, 100

5 drawing off the residue and subjecting it to further cracking but prior thereto passing the residue through a colloid mill where the solid-like particles are broken up into substantially colloidal suspension in the liquid portion of the residue.

10 2. A process of cracking hydrocarbon oil, consisting in subjecting the oil to cracking conditions of temperature and pressure whereby vapors are evolved and solid-like particles are precipitated, removing and collecting the cracked vapors, drawing off the residue containing the solid-like particles cooling the residue, breaking up said particles into substantially colloidal suspensions in the liquid portion of the residue, then subjecting the residue to cracking conditions of temperatures and pressure.
